MUFFLE AND LIKE FURNACE

Henry Wilmot Spencer, Roehampton Lane, London, and Leonard Sherrington Davis, Bexley Heath, England

Application October 8, 1935, Serial No. 44,096
In Great Britain October 9, 1934

19 Claims. (Cl. 263—42)

This invention relates to muffle and like furnaces in which the products of combustion are excluded from the work under treatment by the provision of an inner refractory chamber or muffle around which the products of combustion are circulated.

With the exclusion of muffles of the smaller sizes which are formed in one piece, this type of furnace suffers from the objections that it is difficult to secure the necessary requirement of relatively thin walls and roof or arch with mechanical strength and to maintain the joints of the building units in a gastight condition. Repairs are often difficult and comparatively costly to effect, usually necessitating a substantial dismantling of the furnace and, furthermore, existing types of constructions do not lend themselves to uniform and controllable heating.

Most of the disadvantages in known constructions are due to the necessity of incorporating a muffle roof of sprung construction. The disadvantages of this are well known in ordinary furnace constructions but the objections are of greater consequence when a sprung arch is applied to a muffle as owing to the comparatively thin material which must be employed trouble is experienced in affording adequate support to the side walls due to the thrust of the arch. Even when this is accomplished the life of the muffle may be reduced owing to the compressive stresses present in the muffle. By means of the present invention each individual unit of the muffle is free from stresses induced by adjacent blocks and the side units of the muffle are relieved by thrusts from the arch or roof.

An object of the present invention is to provide a muffle furnace construction adapted to avoid the above objections and to afford a muffle which not only may be readily repaired or renewed but one which is adequately strong and gastight under ordinary working conditions.

A further object of the invention is to provide a furnace construction which is capable of more flexible operation and in which the temperature conditions within the muffle are susceptible of considerable control.

The invention comprises the provision of suspended furnace arch and wall refractory elements upon the arch elements of which are suspended tiles or units and to the wall elements of which tiles or units are keyed to form the muffle and affording passageways through which the products of combustion are intended to circulate.

The invention also consists in a muffle arch comprising refractory tiles or units suspended or

hung from the refractory elements of a suspended furnace arch and affording passageways through which products of combustion circulate.

A feature of the invention lies in the formation of the tiles with parts or webs carrying the suspension or keying means and also forming sides of the passages through which the products of combustion circulate.

It is preferred to combine the above muffle construction with the jacketed suspended arch and wall structure forming the subject of our British Patent application No. 28,908 of 1934 and accordingly a further feature of the invention comprises the provision of an outer jacketing housing for the suspended arch and walls carrying the suspended muffle units of the character indicated and the mechanical circulation of air through the jacket for controlling the temperature conditions and so as to make the heated air available for combustion or otherwise to avoid heat losses.

It is to be understood that the expression "suspended wall element" used herein means a refractory element forming part of the furnace wall as distinct from the arch and supported by means such as a hook or bracket so that the lower blocks do not sustain the cumulative weight of those above.

In the accompanying drawings:—

Figure 1 is a side elevation partly in section of a muffle furnace constructed according to the invention and in combination with an air jacketed suspended roof and wall construction according to our British specification numbered as above.

Figure 2 is a transverse sectional end elevation taken on the lines A—A of Figure 1.

Figure 3 is a fragmentary sectional plan on the lines B—B of Figure 2, and

Figures 4, 5, and 6 are sectional detail views of modified forms of tiles and joints for suspending the muffle arch or wall tiles.

In carrying the invention into effect according to one convenient mode as illustrated in Figures 1, 2, and 3, a framework comprising upright girders 1 and horizontal transverse bearers 2 is provided with an outer wall of insulating blocks or lagging 3. The uprights 1 are provided with angle brackets 4 on which refractory blocks 5 forming the suspended wall of the furnace are hung in known manner. The roof or arch of the furnace is formed by rows of refractory blocks 6 the rear or upper sides of which are provided with recesses in which longitudinal bars 7 are engaged. These bars are slung upon hook

members 8 which in turn are carried by longitudinal rods 9 resting on the bearers 2. The suspended walls and arch are erected as will be seen in spaced relationship with the insulating 5 outer wall 3 affording an air jacket A around the walls and over the roof or arch. The jacket space may, if desired, be provided with baffles for directing the course of the air current.

A fan or blower 10 adapted to be driven at various speeds forces air into the jacket through the 10 branched conduit 11. This air circulates over the roof and down the walls and is preferably supplied through branches 12 to burners 13 for combustion purposes.

15 Instead of driving the fan or blower at various speeds the quantity of air passing through the jacket may be regulated by dampers or valves.

The base of the furnace is provided with chambers 14 divided from one another by partitions, 20 the chambers being provided with burners located alternately on opposite sides of the furnace. The partitions 14 support the floor forming slabs 15 of the muffle or inner chamber 16.

The muffle walls and arch or roof are formed 25 of tile members 17, 18 which are hung from the walls and roof by longitudinally or transversely extending joints. As illustrated the tiles are formed with a facing portion 19 and a rearwardly extending web or webs 20 which terminate rearwardly in a dovetailed (or other) jointing part 21 which fits into corresponding recesses in or between the blocks 5 and 6. The web portions 20 position the facing parts or tile fronts 19 in spaced relationship with the faces of the suspended 30 wall and roof blocks so that passages are formed between the rear of the faces 19 and the front of the blocks 5 and 6, such passages being bounded laterally by the webs 20, thus forming conduits or passages B for the circulation of products 35 of combustion as indicated by the arrows on Figure 2 of the drawings.

The passages formed by the webs provide separate zones for the products of combustion and by the provision of a burner for each passageway 45 the heating of the furnace can be variably controlled.

The dovetail or keying means for the tile members in the suspended blocks may be of various forms and the tile members may have a pair of 50 web parts and keying means so that they are of channel form or they may be of box form with a single keying means.

According to one construction (see Figure 4) the tiles have face portions 19 with web portions 55 20 at each side. One of these web portions terminates in a wedge piece 21a while the other is provided with a T-head 21b. The sides of the tile may be provided with grooves and ribs 22, 23, which engage corresponding ribs and grooves on 60 the adjacent tiles for prevention of the passage of products of combustion. The suspension blocks such as the arch blocks 6 shown in Figure 4 have their sides recessed as at 6a and 6b to receive and correspond with the portions 21a and 21b. According to Figure 5 the parts 19 have webs 20 with angled or flanged pieces 21a and 21b formed at different distances from the face 65 portions 19 of the tiles. In this case the suspension blocks are formed with corresponding recesses 6a and 6b.

In Figure 6 a hollow tile member is shown. This comprises a face portion 19, side portions 20 and a T-piece 21c extending from the back portion 19a of the tile and adapted to engage in T- 70 slots in the arch or wall suspended blocks. In

this form the passages B are totally enclosed in the tile members themselves instead of being formed between the suspended blocks and the rear face of the tiles. This figure also exemplifies the provision of a plurality of gastight jointing means as indicated by the grooves 22 and ribs 23 formed on each of the side faces of the tiles.

The muffle tiles are formed of silicon carbide, fused alumina or other refractory material, and 10 the design, shape and sizes may be modified to suit the requirement of any particular furnace design. Any suitable known jointing or filling material may be used for bedding the tiles. Furthermore, tiles or units of special shape may be 15 formed for completing a row or otherwise to fit corners or other localities.

Having now described our invention what we claim as new and desire to secure by Letters Patent is:

1. A muffle furnace construction comprising suspended arch refractory elements and muffle elements suspended from the arch elements to form a continuous muffle wall and affording passageways through which the products of combustion 25 are intended to circulate.

2. A muffle furnace construction comprising suspended arch refractory elements and muffle elements having a keying connection with said arch elements and cooperating to form a continuous muffle wall with passageways for the products of combustion.

3. A muffle furnace construction comprising suspended arch refractory elements and muffle elements suspended from the arch elements in 35 contacting relation to form the muffle wall and affording passageways for the products of combustion.

4. A muffle furnace construction comprising suspended arch refractory elements and muffle 40 elements having a keying connection with the arch elements, said muffle elements forming a continuous muffle wall surface and passageways for the products of combustion, the inner surface of the suspended arch constituting one side of 45 said passageways.

5. A muffle furnace construction comprising suspended wall refractory elements and muffle elements having a keying connection with said wall elements and cooperating to form a continuous muffle wall with passageways for the products of combustion.

6. A muffle furnace construction comprising suspended wall refractory elements and muffle 55 elements having a keying connection with said wall elements, said muffle elements forming a continuous muffle wall surface and passageways for the products of combustion, the inner surface of the suspended wall constituting one side of said 60 passageways.

7. A muffle arch comprising suspended refractory elements and a muffle wall composed of contiguous elements affording a continuous wall surface and having rearwardly directed parts in 65 keying suspension connection with the suspended elements and forming passageways for the products of combustion.

8. A muffle arch comprising suspended refractory elements the inner faces of which lie substantially in a single plane and having keying recesses therein, and muffle elements in contiguous relation forming a continuous muffle wall surface and passageways for the products of combustion, said muffle elements having rear- 70 75

wardly directed parts of keying form engaging in said recesses.

9. A muffle wall comprising suspended refractory elements the inner faces of which lie substantially in a single plane and having keying recesses therein, and muffle elements in contiguous relation forming a continuous muffle wall surface and passageways for the products of combustion, said muffle elements having rearwardly directed parts engaging in said recesses to afford a keying connection with the suspended elements.

10. A muffle arch construction comprising suspended refractory arch elements and muffle elements suspended from said arch elements to form a continuous muffle wall surface, each of said muffle elements being formed to define a passageway for the products of combustion.

11. A muffle furnace construction comprising suspended arch refractory elements, muffle elements suspended from said arch elements to form a continuous muffle wall surface and affording passageways for the products of combustion, and means forming an air jacket outside the suspended arch through which air may be circulated.

12. A muffle furnace construction comprising suspended arch and wall refractory elements, muffle elements united by keying connections to said arch or wall elements and affording passageways for the products of combustion, and means forming an air jacket outside the suspended arch and walls through which air may be circulated.

13. A muffle furnace construction comprising suspended arch refractory elements, muffle elements suspended from said arch elements to form a continuous muffle wall surface and affording separate passageways for the products of combustion, separate base compartments communicating with said passageways, and burners for said base compartments whereby controllable zones are provided for the products of combustion.

14. A muffle furnace construction comprising suspended wall refractory elements, muffle elements united by keying connections to said wall elements and affording passageways for the products of combustion, separate base compartments communicating with said passageways, and burners for said base compartments whereby con-

trollable zones are provided for the products of combustion.

15. A muffle furnace construction comprising suspended arch refractory elements and muffle elements suspended therefrom, said muffle elements having rearwardly extending webs forming between them a passageway for products of combustion and said webs being formed with dovetail suspension means for engagement with said arch elements.

16. A muffle furnace construction comprising suspended wall refractory elements and muffle elements having a keying connection with said wall elements, said muffle elements having rearwardly extending webs forming between them a passageway for products of combustion and said webs being formed with dovetail keying means for keying connection with said wall elements.

17. A muffle furnace construction comprising suspended arch refractory elements and muffle elements suspended therefrom to form a continuous muffle wall, said muffle elements comprising a relatively thin tile of box section adapted to form a passageway for the products of combustion and having rearwardly extending means forming a suspension connection with the arch elements.

18. A muffle furnace construction comprising suspended wall refractory elements and muffle elements arranged to form a continuous muffle wall and having a keying connection with said wall elements, said muffle elements comprising a relatively thin tile of box section adapted to form a passageway for the products of combustion and having rearwardly extending means forming a keying connection with the wall elements.

19. A refractory element for a muffle furnace comprising a relatively thin tile having rearwardly extending webs forming between them a passageway adapted to convey the products of combustion for heating the muffle, said webs being of different but complementary shape and adapted, when the webs of adjacent elements are placed in contiguity, to afford dovetail suspension means for the refractory elements.
